UNITED STATES PATENT OFFICE.

DANIEL OTTO, OF BLOOMINGTON, ILLINOIS, ASSIGNOR TO JOHN F. WHITE, OF BLOOMINGTON, ILLINOIS.

PORTABLE DERRICK.

No. 800,672.

Specification of Letters Patent.

Patented Oct. 3, 1905.

Application filed December 26, 1903. Renewed September 1, 1905. Serial No. 276,771.

To all whom it may concern:

Be it known that I, DANIEL OTTO, a citizen of the United States, residing at Bloomington, in the county of McLean and State of Illinois, have invented certain new and useful improvements in Portable Derricks, of which the following is a specification, reference being had therein to the accompanying drawings.

This invention relates to an improvement in portable derricks for grain-elevators, and is designed more particularly for use in connection with that type of grain-elevators which is in itself portable and designed to receive grain from a wagon and elevate the same to a bin or other depository.

The present invention contemplates a structure which is so fashioned that in the act of transporting the elevator the derrick as such may in part serve as a vehicle onto which the elevator is deposited for transportation and also a construction whereby with facility the derrick can be raised properly positioned and hereafter the elevator drawn up to the proper inclination. Incidentally, the invention is of such a character that its structural arrangements and connections are such as to render it light, strong, and convenient for handling and transporting.

In the accompanying drawings, Figure 1 illustrates the invention in elevation. Fig. 2 is a rear view. Fig. 3 is a view similar to Fig. 1, showing the parts lowered; and Fig. 4 is a similar view showing the parts in position for transportation.

A in the drawings designates a base member or shaft, carrying on its outer end suitable truck-wheels B. Secured to this shaft A are two uprights C C', converging toward their upper ends and there firmly united, a small cross-bar c being interposed between the extreme ends. These uprights may be braced by suitable parallel upright braces D D', springing from the shaft A and connected fixedly to the sides of the uprights C C' at points intermediate the ends of the latter.

E E' designate diagonals connected to the upright braces D D' midway and extending outward, their extreme lower ends being formed with curved portions, as at E², and provided with seats or supporting-blocks E³. The runner or curved edges of the diagonals E E' are positioned on a plane with the wheels B. Extending from the diagonals E E' rearwardly are the braces F F', their forward ends being

removably connected to the lower ends of the upright braces D D', thus forming in the combination a truss structure rendering the derrick rigid and maintaining it in its elevated position. These bars or braces are conveniently formed with a series of apertures f, through which the connecting-pin f' may be passed, connecting the same removably with the axle or shaft A through the bases of the upright braces D D'. By this means the derrick proper can be varied as to its inclination.

G designates the elevator, having the pivoted drag H thereon of any approved or well-known type. The elevator is supported on the supporting-blocks E³ of the diagonals E E' in any convenient manner, conveniently by the operating-shaft S, as shown. In this connection suitable boxes are to be employed, although it is manifest that any suitable means for supporting the elevator on the lower end of the diagonals may be used. The upper end of the elevator carries a bail J, to which a suitable hoisting-rope K is attached, the same passing over pulley-blocks supported by the short cross-bar at the upper end of the derrick. The supporting-rope in turn is carried down into operative position.

In operation the elevator when adjusted for use is in the position shown in Fig. 1, the lower portion resting on the diagonals 85 and the upper portion being carried by the derrick proper. In this position the elevator can by proper manipulation of the rope be adjusted to any convenient angle or lowered to the position shown in Fig. 3 for transportation. When the elevator is lowered, the drag is turned back onto the same, the braces F F' are uncoupled from the upright braces D D', and the wheeled axle is thereupon turned or moved backward, the pivotal point 90 between the diagonals and the braces serving as the center around which the axle may turn. This act lowers the upright derrick members, carrying the lower ends toward the rear and the upper ends down on the outer end of the elevator, as shown in Fig. 4. In this position by applying the draft power to either end of the derrick the same can be readily transported from place to place.

From the above-described construction, it will be observed that the portable derrick comprises, essentially, two frames, one consisting of the upright braces and the other of

the diagonal braces, and that the latter are connected pivotally to the braces D D' of the upright members, so that the upright derrick member can be folded down in the manner 5 above suggested.

Manifestly obvious modifications can be made—as, for instance, certain parts can be eliminated, others added—without departing from the nature and principle of the invention. It is also to be understood that while one form of the invention has been shown, the same is not limited in any respects to the particular arrangement and construction here delineated.

15 Having thus described the invention, what is claimed as new, and desired to be secured by Letters Patent, is—

1. In a portable derrick for portable elevators, the combination with a derrick having suitable wheels at its lower end, of forwardly-extending members pivotally connected with the derrick, and a brace located below the forwardly-extending members and removably connecting the derrick and the 25 forwardly-extending members.

2. In a portable derrick for grain-elevators, the combination with a shaft, of derrick-uprights secured thereto, diagonal members extending therefrom, their lower ends being 30 fashioned to receive the lower end of the elevator, detachable braces between the diagonals and the uprights, and an elevator substantially as described.

3. In a portable derrick for portable elevators, the combination of a wheel-shaft, of a 35

derrick member connected thereto, diagonally-arranged supporting members extending from the derrick, a detachable brace interposed between the derrick member and the diagonal members, an elevator, and means connected with the derrick for raising and lowering the elevator.

4. In a portable derrick for portable elevators, the combination with a wheel-shaft, of inclined derrick members carried thereby, parallel braces between the inclined members, diagonal supporting members extending from the parallel braces forward, and removable brace members between the diagonal members and the shaft.

5. A portable derrick for portable elevators comprising a derrick member and forwardly-extending supporting members, a shaft to which the said members are connected respectively, a brace member detachably connecting the said other two members, and an elevator carried by the derrick.

6. In a portable derrick for portable elevators, two frames arranged at an angle to each other and pivotally associated so that the same can be folded, and a detachable brace member between the frames and adjustably connected to one of the frames.

In testimony whereof I affix my signature in presence of two witnesses.

DANIEL OTTO.
